UNITED STATES PATENT OFFICE.

STEPHEN JOHN HINMAN, OF WESTVILLE, CONNECTICUT.

PIPE ATTACHMENT FOR WRENCHES.

SPECIFICATION forming part of Letters Patent No. 759,442, dated May 10, 1904.

Application filed September 23, 1903. Serial No. 174,273. (No model.)

To all whom it may concern:

Be it known that I, STEPHEN JOHN HINMAN, a citizen of the United States, residing at Westville, in the county of New Haven and State 5 of Connecticut, have invented new and useful Improvements in Pipe Attachments for Wrenches, of which the following is a specification.

My invention relates to certain new and useful improvements in pipe-wrench attachments, the object being to provide a simple, inexpensive, and effective attachment adapted to be secured to the shank of an ordinary monkey-wrench and to fit between the jaws thereof 15 and provided with intermediate serrated jaws adapted to grip the pipe, so that the wrench to which my attachment is secured may be effectively used upon round pipes or rods in the same manner as the ordinary wrench is 20 used upon angular nuts.

A further object of my invention is to provide a simple device of the class described that can quickly and easily be secured to any wrench and used in connection therewith.

25 My invention consists in the novel construction and arrangement of parts hereinafter fully described, illustrated, and claimed.

In the drawings accompanying the specification and forming a part thereof, Figure 1 30 is a side elevation showing my device attached to an ordinary monkey-wrench. Fig. 2 is a vertical section of my improvement, and Fig. 3 is a perspective of the parts detached.

Letters of reference indicate corresponding 35 parts in all the figures of the drawings.

a designates the shank of an ordinary monkey-wrench, to which my device is shown attached.

b is the rigid member on which is pivoted, 40 by means of a pin or bolt *c*, which may be secured to the rigid member in any suitable manner and may be removable, a series of serrated angular jaws *d*, between which are disposed a series of spacing-pieces *e*. These spacing- 45 pieces are of the same shape as the jaws *d*, but are formed so as to leave a blank space between the serrated jaws at the point where the teeth are set, as shown at *f*, in order to permit the fur of the metal caused by the gripping of the

teeth upon a pipe or rod to settle between the 50 jaws.

g is a removable member with a notch *h* therein, as shown, which allows it to be fitted snugly on the pin or bolt *c*, the end of which extends beyond the serrated jaws for that purpose. The removable member *g* is also provided with a locking-clip *i*, adapted to engage with and settle into a kerf *k* in the end of the rigid member in order to hold the removable member firmly in place when the device is secured to a wrench.

In operation the rigid member *b* is placed upon the shank of a wrench, so as to bring the back of the serrated jaws tight against the shank with the teeth facing the opening between the jaws of the wrench. The device is so constructed, it will be readily observed, that the back thereof may rest upon either the rigid or removable jaw of the wrench, as may be desired. The removable member is then put 70 in place, with the notch *h* fitting over the end of the pin or bolt *c*. The device is then effectively secured in place on the wrench by pressing the locking-clip *i* into the kerf *k*.

My device may be made of any desired size, 75 so that it will fit any ordinary wrench, and while when detached the serrated jaws and the spacing-pieces swing loosely on the pin or bolt *c* it will be observed that when the same is fitted on the shank of a wrench the jaws and 80 spacing-pieces are held rigidly and firmly in place and are immovable.

Certain modifications of form and arrangement of parts may suggest themselves to the skilled mechanic; but such modifications and arrangements come well within the scope and spirit of my invention as disclosed and claimed, and I therefore do not desire to be limited to the precise construction and arrangement shown.

Having thus described my said invention, what I claim as new, and desire to secure by Letters Patent, is—

1. A pipe-wrench attachment for monkey-wrenches, having a plurality of angular serrated jaws disposed between two side members, substantially as described.

2. A pipe-wrench attachment for monkey-

wrenches, having a jaw with a plurality of serrations, and with intermediate spaces between the serrations, substantially as described.

3. A pipe-wrench attachment for monkey-wrenches, having a plurality of angular serrated jaws disposed between a rigid and a removable member, and a plurality of spacing-pieces disposed between the jaws, substantially as described.

10 4. A pipe-wrench attachment for monkey-wrenches, having a plurality of angular serrated jaws disposed between two side members, a plurality of spacing-pieces disposed between the jaws, and a locking-clip, substantially as described.

15 5. A pipe-wrench attachment for monkey-wrenches, having a plurality of angular serrated jaws disposed between a rigid and a removable member, a plurality of spacing-pieces disposed between the jaws, and a locking-clip, substantially as described.

20 6. A pipe-wrench attachment for monkey-wrenches, having a plurality of serrated jaws disposed between two side members, and provided with intermediate spaces between the serrations on the different jaws, substantially as described.

25 7. A pipe-wrench attachment for monkey-

wrenches, having a rigid and a removable member, a plurality of angular serrated jaws pivoted between the members, a plurality of spacing-pieces disposed between the jaws, and a locking-clip, substantially as described.

30 8. A pipe-wrench attachment for monkey-wrenches, having a plurality of serrated jaws disposed between two side members, a pivot, a plurality of spacing-pieces disposed between the jaws, and a locking-clip adapted to engage with a kerf, substantially as described.

35 9. In a pipe-wrench attachment for monkey-wrenches, a rigid member provided with a pin, a plurality of angular serrated jaws with spacing-pieces disposed between them, and adapted to swing on the pin, a removable member, a notch or kerf therein adapted to fit on the end of the pin, and a locking-clip adapted to engage with a kerf in the end of the rigid member, substantially as described.

40 In testimony whereof I have signed my name to this specification in the presence of two sub- 45 scribing witnesses.

STEPHEN JOHN HINMAN.
